(57) **CLAIM**

The ornamental design for a measuring device, as shown and described.

DESCRIPTION

FIG. 1 shows a front view of my design for a measuring device;

FIG. 2 shows a rear view thereof;

FIG. 3 shows a bottom, front and right side perspective view thereof;

FIG. 4 shows a top, rear and right side perspective view thereof;

FIG. 5 shows a left side view thereof; and,

FIG. 6 shows a front and left side perspective view thereof. The features shown in broken lines show environmental structure only and form no part of the claimed design.
